UNITED STATES PATENT OFFICE.

IRENE WHETSTONE, OF CHICAGO, ILLINOIS.

SELECTIVE UNIT INDICATION FOR FILING AND OTHER PURPOSES.

Application filed January 12, 1920. Serial No. 351,079.

The invention has general reference to the indication or designation of any one of a plurality of units selectively, through the medium of manually operable control means such as a keyboard and mechanism acting in response to such manual control to effect the selection of the desired unit.

In its preferred embodiment the invention is described in relation to a system of distribution adapted for use in such instances as in the filing of cards, letters and other papers which it is desired to preserve for ready reference; and one object of the invention is to produce a distributing system involving a simplified method of designating the filing folders or other separating units, which it is desired to select, and an apparatus by means of which the method may be carried out to accomplish the selection with maximum efficiency. Herein the invention is illustrated and described for convenience in connection with a filing system.

According to the methods of filing as commonly practiced heretofore, especially where, as in large mail order houses, the correspondence and other matter to be filed is voluminous, the time required to properly do the work has been very great and even with the exercise of great care by an expert file clerk many errors are unavoidably committed. Obviously, therefore, the cost of maintaining such file departments has been very high, and the system as heretofore employed quite unsatisfactory. One aim of the present invention is to reduce to a minimum the amount of time necessarily expended not only in the selection of the proper place in the drawer or other file container in which a given paper belongs, but in the preliminary work of arranging the material which is to be filed; also to eliminate substantially the commission of errors in carrying on the work.

An important objection to the methods of filing as heretofore commonly practiced is that the filing clerk has made the selection of the desired folders or units wholly by sight, the eye being depended upon as it runs over the multiplicity of guides to make the proper selection. Owing, however, to the confusion naturally resulting from the presence of a great many file units similarly designated, coupled with the ever-present aim to accomplish the filing with the expenditure of as little time as possible, many errors occur. To overcome to a large extent this tendency on the part of the file clerk to

commit errors and at the same time substantially lessen the amount of work required in making the selection of a given file unit, use is made, in carrying out the invention, of the principle which has become well recognized, in the art of typewriting and in other arts, that the fingers of the operator can be trained with reference to a keyboard to attain a high degree of accuracy at a relatively great speed without the aid of the eye. The invention in this embodiment, therefore, contemplates the selection of the file units through the operation of a keyboard with which is associated suitable electro-magnetic means together with suitable mechanism for operating selecting devices which are movable into engagement with the file units successively, in a filing drawer or other container, the depression of the proper keys and the subsequent actuation of the operating mechanism being arranged to effect the selection of the desired file unit in which the material to be filed is placed or from which it is to be withdrawn.

Moreover, where the matter to be filed is voluminous, previous methods have required the sorting and hence the handling of the material a number of times before it is finally distributed to the proper places in the file drawer. For example, the subdivisions of the letter "C" in the name "Crete" may require sorting and handling three consecutive times; first, under "C", then under "r", and next under "e". For this purpose sorting trays with identifying guides are sometimes employed and as the material to be filed is sorted, a card bearing the filing designation "Crete" is distributed with other matter first according to the first subdivision, then re-sorted according to the second subdivision, and finally re-sorted according to the third subdivision. When the material to be filed has thus been sufficiently subdivided, it is finally placed in the proper place in the filing drawer. Such preliminary sorting is obviously objectionable because of the large amount of time required, and the opportunity offered for error; and it is an important aim of the present invention to provide a system which will overcome this objection by eliminating the preliminary sorting.

A more specific object of the invention is to provide an apparatus which may be constructed at a comparatively low cost and which is very rapid and otherwise efficient in operation.

Another object of the invention is to provide a filing unit consisting of a combined filing folder and guide for receiving the material to be filed, which eliminates the use of the customary guide and also reduces to a minimum the number of units required and hence the cost of the filing equipment, and which, furthermore, consumes a minimum amount of space in the filing drawer.

10 The objects of the invention thus generally stated, together with other and ancillary advantages which will be apparent as the description proceeds, are attained by the construction and arrangement illustrated in 15 the accompanying drawings forming part hereof.

It will be understood, however, that the apparatus as illustrated constitutes an illustrative embodiment only of the invention, 20 and that it is not intended that in the interpretation of the appended claims they shall be limited to the particular means herein disclosed nor to the particular use selected for purposes of illustration.

25 In the drawings, Figure 1 is a fragmentary top plan view of an apparatus embodying the invention. Fig. 1^a is a detail view showing some of the electrical contacts employed. Figs. 2 and 3 are transverse vertical sections through different portions of the apparatus, the drawer of the filing cabinet being in Fig. 2 shown supported in operative position in the supporting casing. Fig. 3^a 30 is a detail view of one of the keys and its stem. Fig. 4 is a fragmentary vertical longitudinal section through the apparatus showing a portion of the operating mechanism. Fig. 5 is a similar view showing the operating mechanism in two different vertical planes through the apparatus. Fig. 6 is 35 a fragmentary horizontal section taken on the line 6—6 of Fig. 3. Fig. 7 is a fragmentary horizontal section taken substantially in the plane of line 7—7 of Fig. 3. Fig. 8 is a fragmentary horizontal section showing 40 particularly the means for holding the operating keys depressed, and the releasing means therefor. Fig. 9 is a plan view of the combined file receptacle and guide. Fig. 9^a 45 is a similar view of the same partially folded. Fig. 10 is a fragmentary top plan view of a file drawer equipped according to the invention. Fig. 10^a is a fragmentary bottom view of the folder when folded. Fig. 11 is 50 a detached view of a sheet of insulation such as is used between the several file units. Fig. 12 is a diagrammatic plan of the invention showing particularly the electrical connections of the selective mechanism forming 55 part of the invention.

Brief description of invention.

Briefly, the apparatus comprises a casing 13 divided longitudinally thereof by means 65 of a partition 14 (Figs. 2 and 3) into sepa-

rate compartments 13^a and 13^b, one for receiving the filing drawer or other receptacle containing a plurality of guides or units 15 to be operated upon, and the other compartment enclosing the greater portion of the operating mechanism of the apparatus. Mounted transversely of the casing for movement longitudinally thereof, are a plurality of selector bars 16 (Figs. 1 and 12) 70 each carrying a plurality of contact devices, and an operating rod 17 extending longitudinally of the casing within the compartment 13^b is adapted to operate the selector bars 16 when connected therewith by means of suitable locking mechanism 18 (Fig. 2). This locking mechanism is operable by the depression of certain of the keys of a keyboard 19 which are operatively associated with mechanism within the compartment 13^b 75 suited for this purpose. The depression of certain other keys is adapted to establish with a predetermined filing unit in the filing drawer a normally open electric circuit, and this circuit is arranged to be closed by the contact device of the proper selector bar 16 80 corresponding to said unit, as the bar is moved by the operating rod 17; and upon the closing of such circuit, one of a set of electromagnets 20 in said circuit acts to release the locking mechanism and thus disconnect the selector bar from the operating rod. In the continued movement of the rod by the operator, the selector bar thus remains positioned over the file in which the filing material is 85 to be placed or from which it is to be withdrawn. Upon the operating rod 17 are fixed a plurality of abutments 21 adapted in the movement of the rod to its initial position to also carry the selector bars to their respective initial positions, and also carried by said rod is a fixed abutment such as a collar 22 adapted when the rod is moved to the limit of its operating stroke to actuate mechanism to restore the keys to their initial 90 operative position and thereby break the electric circuit established by the selector bar. 95

In the present embodiment of the invention, there is shown, by way of example, a filing system in which the consecutive file units are designated numerically, but it will be understood that any preferred designating characters may be employed. Thus, referring to Figs. 10 and 12, the apparatus is shown as adapted for use with file drawers in which the file units are arranged in divisions, each providing one hundred separators or filing receptacles, the first hundred being designated generally A, the second B, the third C, and so on. A selector bar 16 is provided for each division (Fig. 1), each bar being provided with a plurality of contact members arranged to coact with the respective guides which are arranged in sets of ten. Upon the depression of the proper keys 100 for the selection of a certain file or guide, a 105

normally open electric circuit is formed which may be closed by the selector bar in its movement by the operating rod, whereupon the electro-magnet in the circuit acts to release the selector bar in the desired position.

The invention in detail.

As heretofore stated, the casing 13 is provided with a central partition 14 to form 10 separate compartments 13^a and 13^b. The casing is also provided with a top 24 through which at the forward end of the apparatus extend the stems 25 of the operating keys, and over the compartment 13^a 15 the top has an opening 23 to permit of the free inspection of the files. Referring to Figs. 1, 2 and 3, the compartment 13^a of the casing is open at its forward end whereby to permit of the insertion of a filing drawer 26 20 (Fig. 2). For receiving said drawer, the compartment is provided in its lower portion upon opposite sides thereof, with a pair of angular supporting rails 27 which are pivotally mounted upon links 28 and at their rear 25 ends shaped to provide stops 29 for limiting the rearward movement of the drawer relative thereto. The links are inclined forwardly slightly so that as the drawer is moved to the rearward limit of its movement relative to its supports 27, the continued movement thereof will cause the said members to swing upwardly upon their links 28 from the position shown in Fig. 3 to that shown in Fig. 2, in which the links engage stops 28^a 30 (Fig. 6). Carried by said supporting rails 27 are a plurality of upright members 30 having at their upper ends cam portions 31 adapted to actuate means for engaging the file units in the drawer for the purpose of 35 making electrical contact therewith, as will be presently described.

It is understood, of course, that each drawer of the filing system is especially equipped so that when it is placed in operative position within the casing compartment 13^a it forms with the mechanism of the casing the complete apparatus. Referring now to Figs. 2, 9, 9^a, 10 and 10^a, particularly, a 40 special form of file unit which is adapted to consume as little space as possible is preferably employed, and moreover is especially constructed for the purpose of enabling the formation of the electro-magnetic circuits in which said units are placed in the operation of the keys. Said units are consecutively arranged in a predetermined order as 45 from 1 to 100 in each division, and the division in turn is subdivided into sets of units of a given number as, for example, 10, and each unit bears a designation, as, for example, a numeral.

Referring now to Fig. 9 each set of units is preferably formed from a single sheet of material adapted to be folded along a central score 32 and divided along relatively

staggered lines 33 to form a plurality of flaps 34. The flaps on each side of the score 32 are alternately numbered and the set is formed by folding the flaps successively into engagement with each other. Thus, with 70 the blank lying flat upon a surface, the 10 flap is first swung upwardly and then downwardly over the 11 flap, the 11 flap together with the 10 flap are swung downwardly and forwardly until the rear side of the 11 flap 75 engages with the 12 flap; the 12 flap, together with the preceding flaps are then swung upwardly and rearwardly into engagement with the 13 flap, and so on, forming between adjacent flaps when folded 80 guides or receptacles for receiving material to be filed. Herein the blank from which each set of units is formed is made of metal so as to constitute a conductor for electric current, and to insulate the several sets from 85 each other, sheets of insulation 15^a (Fig. 10) may be employed. It will be understood, however, that other materials for the units may be adopted and suitable connections for conducting the current to the respective units 90 employed. Upon opposite sides of the drawer, and also upon the bottom, sheets 15^b and 15^c of insulating material are employed (Figs. 2, 10 and 11). Separate sheets are 95 provided for each division and preferably the side sheets are corrugated or roughened as shown in Fig. 11 to receive the opposite edges of the insulated sheets 15^a, whereby to maintain the sets in upright position. As shown clearly in Fig. 9, each of the flaps is 100 provided with a tab 35 for receiving a designating character. As shown in Fig. 2, the upper portions of the file units project a short distance above the upper edge of the drawer 26, and above the opposite walls of the 105 drawer adjacent the opposite sides of said sets of file units is mounted a pair of bars 36 each supporting a conduit 37 carrying wires 38 one for each of the sets of units in a division, and arranged to be connected 110 therewith to form electro-magnetic circuits which are arranged to be set up to accomplish the selection of a given unit. Herein each of the bars 36 carries a plurality of ribs 39 each adapted to be engaged by a finger 40 on one of the sets of file units, the fingers 40 being so arranged relative to each other and the ribs 39 that an electrical connection is made between each set and its proper rib. Said ribs are respectively connected to the wires 38 in the conduit 37. 115

Referring to Fig. 12, the wires 38 are shown diagrammatically as having a connection each with a certain one of the sets of units in each division, so that the several 120 corresponding sets of all of the divisions may be controlled by a single key as will appear more fully hereinafter.

In order that effective electric contact between the ribs 39 and fingers 40 shall be 125

made, the bars 36 carrying the ribs 39 are mounted for movement into engagement with the file sets when the drawer is moved into its operative position in the apparatus.

5 For this purpose, the bars 36 are carried by rods 41 mounted on the walls of the compartment 13^a, with tension springs 42 tending to draw the bars at all times toward said walls. The cam portions 31 on the upper 10 ends of the bars 30 which are carried by the supporting bars 27, are arranged to engage with blocks 43 carried by the bars 36 so as to force the latter inwardly into engagement with the sets of file units.

15 The selector bars 16 are mounted for movement longitudinally of the casing 13, being for this purpose guided by a longitudinal guideway 44 provided on one wall of the casing and a guideway 45 formed by means 20 of a slot in the partition 14 in the casing. Each bar 16 carries a plurality of switch members or contact devices 46 (see particularly Fig. 5) which are arranged to engage with the tabs 35 of the units 15 and thereby 25 complete an electric circuit. In the diagrammatic view (Fig. 12) said contact devices 46 are indicated by arrows, and it will be seen that they are arranged so that in the longitudinal movement of the bar in the casing, each device will engage successively 30 with the corresponding units of the several sets contained in each division. Each of said contact devices is connected by means of suitable wiring 46^a (Figs. 4 and 5) with 35 a contact member or clip 47 on the upper right hand portion of the selector bar (Figs. 2 and 5) the latter being arranged to slidably engage with bus-bars 48 upon the under side of the top wall 24 of the casing. In 40 the diagrammatic view in Fig. 12, the clips 47 are indicated by arrows and the bus-bars 48 by parallel lines.

45 Within the rearward portion of the compartment 13^b is provided a battery 49 (shown diagrammatically only, Fig. 12), and the wires 38 and 48 are arranged to be connected in circuit with said battery by means of the keys 19 (Fig. 1). For this 50 purpose each of the wires 38 is connected to a contact member 50 (Figs. 3 and 6) with the exception of the one (38^a) which is connected with the first set of each division, which is in circuit with the battery when the keys are in their normal or inoperative 55 position for a purpose which will herein-after be described. A continuous contact member 51 (Fig. 6) is connected at all times in circuit with the battery 49 (Fig. 12) and the contact members 50 are arranged to be 60 connected with said member 51 by means of switch members 52 carried by the stems 25 of the tens keys 19^b. Similarly, the bus-bars 48 are connected respectively with contact members 53, and a continuous contact 65 member 54, which is at all times in circuit

with the battery 49, is arranged to be connected with said members 53 by means of switch members 55 carried by the stems of the units keys 19^a. Here also, however, one wire 48^a, which is connected with the first or unit of each division, is at all times in the battery circuit when the keys 19^a are in inoperative position. This connection of the zero wires 38 and 48^a in circuit with the battery when the keys are not depressed is 70 provided so that when it is desired to select the first unit of each division, as for example the zero unit of division A or the 100 unit of division B, such unit will be in circuit. The means for forming such circuits with the zero units of the several divisions when the keys are in inoperative position may comprise sets of staggered contact members 56 and 57 (Figs. 1^a and 3) upon the under side of the top wall 24 of the casing 13, 75 which are arranged to be closed by switch members 58 and 59 carried by the stems of the keys 19^a and 19^b respectively. Normally the keys are held in their uppermost or inoperative position by compression 80 springs 60 bearing between collars 61 on the key stems and the bottom of the housing 62 through which the key stems pass. At their lower ends the key stems pass through a 85 plate 63 supported a short distance above the bottom of the casing. Said plate also serves as a support for the contact members 50, 51, 53 and 54.

It will be seen that by depressing any one of the tens keys 19^b, a desired set 15 in each 100 division may be placed in circuit with the battery 49, and by depressing a units key 19^a, the proper contact member for a given unit of such set may also be placed in said circuit. The circuit, however, remains open until 105 closed by a contact device 46 upon one of the selector bars 16 in the movements of the latter, and such closing of the circuit energizes the electro-magnets 20 and the proper one acts to effect a release of the selector bar 110 from its moving means and thus the stoppage of the selector bar in position over the particular file unit desired. The means for actuating the selector bar and for causing the release of the same will now be described.

115 Referring to Figs. 2 to 5 particularly, the operating rod 17 is mounted for longitudinal movement in the upper portion of the compartment 13^b, extending at its forward end through the forward wall of the casing 120 and provided with a hand portion or knob 64 so that the rod may be readily grasped by the operator. Depending from each of the selector bars 16 within the compartment 13^b is a pair of spaced ears or plates 65 apertured to receive the rod 17, and carried by said plates is one member 66 of the latch mechanism 18 which is operable by the depression of one of the keys 19^b to selectively 125 connect one of the bars 16 with the rod 17.

To this end the latch mechanism comprises a latch member 66 pivotally mounted between the plates 65 on a pivot 65^a and slidably longitudinally of a rod 67 forming part of a swingable cradle operatively associated with the keys 19^c. A cradle is provided for each of the selector bars and comprises in combination with the rod 67 a sleeve 68 mounted upon a shaft 69 suitably mounted in the casing, said sleeve having arms 70 and 76 fixed thereto at opposite ends, which carry at their free ends the rod 67.

The connections between said cradles and their respective keys 19^c may comprise key bars 71 one for each of said keys 19^c and connected therewith by means of crank arms 72, rock shafts 72^a and arms 73 (Figs. 3, 4 and 6). The latter are pivoted on the shafts 72^a which extend between the partition 14 and an upright longitudinal plate 74. Each of said key bars 71 is arranged to swing a finger 75 fixed upon a rock shaft 75^a (Figs. 6 and 7) also carried by the partition and plate 74 and having rigid therewith an arm 75^b pivoted to the key bar 71. The free end of said finger 75 engages with the underside of the arm 76 (Fig. 2) which is rigid with the sleeve 68 of the cradle, so that in the depression of one of the keys 19^c, the corresponding finger is caused to swing upwardly carrying with it the arm 76 and thereby imparting to the rod 67 of the corresponding cradle a swinging movement. In such movement the latch member 66 is swung into engagement with the rod 17, and the latter, in order to permit of the locking of the rod against longitudinal movement relative to the latch members, and hence to the selector bar, is provided with a plurality of notches 77, one for each of the latch members 66. It will be seen that by reason of the sliding connection of the latch member 66 with the rod 67, the selector bars are free to be moved longitudinally in the operation of the rod 17.

As the arms 76 are swung upwardly by the fingers 75 in the operation of the keys 19^c, they are arranged to be engaged by a latch member 78 (Fig. 2) engaging with a pin 79 on the arm 76. A tension spring 80 extending between the arm and the bottom of the casing tends to draw the arm downwardly and thus hold the pin 79 in engagement with the latch member. By this mechanism it will be seen that upon the depression of any one of the keys 19^c its corresponding latch member 66 will be moved into locking engagement with the rod 17 and held in such engagement by a latch member 78 engaging with an arm 76. Accordingly, upon the operation of the operating rod 17 the selector bars 16 when connected thereto are moved forwardly and their contact members 46 moved successively into engagement with the corresponding units of the several sets of their divisions. In order that such connec-

tion of one of the selector bars with the operating rod 17 shall be released when a contact member 46 engages the unit which it is desired to select and thereby cause a stoppage of the bar while in engagement with such unit, the latch members 78 are arranged to be actuated by the electro-magnets 20. These latter (Fig. 12) are arranged in parallel in the battery circuit, and by reason of the closing of the circuit effected by a contact member 46 engaging with a given unit, all of the electromagnets are actuated to release whichever latch member 78 has been engaged with an arm 76. To this end the latch member is pivoted upon a stationary bracket 80 carried by the electro-magnet, and is rigid with a keeper bar 82 which is normally held in inoperative position by means of a spring 83. The operation of the magnet upon the closing of the circuit thus causes the latch member 78 to become disengaged from the pin 79 of the arm 76, whereupon the spring 80 swings the arm and thereby the cradle to cause the latch member 66 to swing out of engagement with its notch 77 in the operating rod 17.

In order that the selector bar 16, which travels over the first division A, will be moved in the operation of the operating rod 17 when none of the keys 19^c are depressed (the latter being primarily adapted to select the proper bar for the divisions other than the first) a special latch mechanism 18^a is provided which normally connects the operating rod to the first selector bar 16, and this latch mechanism is arranged to be operated upon the depression of any one of the keys 19^c so as to release said connection. The means for accomplishing this result comprises (see Figs. 3 and 4) a finger 84 rigid with a transverse shaft 85 carried between the partition 14 and the plate 74, and the latter has fixed thereon a plurality of arms 86 each carrying a pivot stud 87 operatively engaging in the forward end of an arcuate slot 88 in one of the key bars 71. The slots 88 are provided to permit of relative movement between the key bars. The free end of the finger 84 passes through an opening (Fig. 3) in an arm 76^a carried by the sleeve 68 of the cradle for the selector bar of division A. A latch member 66^a slidably relative to the rod 67^a of said cradle normally engages with the operating rod 17, being held in such position by means of a coiled tension spring 80^a interposed between the arm 76^a and an extension 62^a of the housing 62, through which the stems 25 of the keys 19^c pass. Upon the downward movement of the arm 86 in the operation of the finger 84 by the depression of any one of the keys 19^c, the latch member 66^a is moved out of engagement with the operating rod 17. By this arrangement, it will be seen that when none

of the keys 19^a are depressed the movement of the operating rod 17 will carry the first selector bar 16 into engagement with the units of its division; and when any one of the keys 19^a is depressed so as to effect a connection between the operating rod and one of the other selector bars, the connection between the first selector bar and the operating rod is released.

For the purpose of locking the keys 19^a and 19^b in their depressed position until especially released, means is provided (Figs. 3 and 8) comprising a latch member 89 for each of said keys, the stems 25 of the latter being provided with notches 90 in their edges (Fig. 3^a) to receive said latch members when forced by means of leaf springs 91. Said springs are carried by the latch members and their free ends engage in notches 92 formed in a longitudinally slidable plate 93 mounted upon the under side of the housing 62 within the compartment 13^b. Said plate has a laterally extending arm 94 which projects into the path of movement of the collar 22 on the operating rod 17, and the parts are so arranged that as the rod approaches the extreme end of the forward stroke, the collar engages with the arm 94 to cause the plate 93 to move forwardly whereby the engagement of the rear ends of the notches 92 with the latch members disengages the latter from their notches in the key stems. The latch members may be pivoted at 95 for convenience upon the under side of the bottom wall of the housing 62 (see Fig. 3); and a tension spring 96 between the wall of the housing and the arm 94 may be provided to normally move the plate 93 into its normal or locking position.

The operation.

Referring to Fig. 1, a filing drawer containing a plurality of file units arranged in sets and the latter grouped to form divisions as A, B, C, etc. with permanent partitions 97 therebetween, (Figs. 10 and 12), is inserted into the compartment 13^a of the casing of the apparatus through the open forward end thereof, upon the supporting rails 27. As the drawer is moved into engagement with the stops 29 at the rear ends of said rails, the latter are swung upwardly upon their links 28 to elevate the drawer into the position shown in Fig. 2. In this upward movement of the drawer, the cam members 31 carried by the supporting rails 27 engage with the longitudinal bars 36 so as to move them and the ribs 39 carried thereby inwardly whereby to cause the ribs 40 to make electrical contact with the fingers 40 carried by the several sets 15 of file units. The bars 36 with ribs 39 and the fingers 40 are for convenience divided and arranged on opposite sides of the drawer.

Should it be desired to select unit 123, for

example, the operator depresses the 100 key of the keys 19^a; the 20 key of the keys 19^b; and the 3 key of the keys 19^a. In this operation the second or division B selector bar 16 is connected to the operating rod 17, through the medium of the finger 75, connected to the key bar 71 of said 100 key, and the associated latch mechanism 18. Moreover, the set 15 of file units containing the unit 123 is placed in circuit with the battery 49 by a switch member 52 which is carried by the stem of the 20 key, said set of units being connected by a wire 38 to the contact 50 which is arranged to be connected by the switch member 52 with the contact member 51 connected to the battery. The depression of the 3 key places the fourth contact device 46 of the division B selector bar in circuit with the battery through the medium of the switch member 55 and contact members 53 and 54, the member 53 being connected by means of the particular bus 48, which makes contact with the proper contact device on the selector bar, and the member 54 being connected with the battery, with the set of electro-magnets 20 interposed in the circuit.

The division B selector bar 16 having thus been connected to the operating rod 17, the forward movement of the latter carries the contact devices thereof into engagement with the units of the several sets of the division until the proper contact device engages with the unit 123. Immediately upon such engagement, an electro-magnetic circuit is closed and an electro-magnet 20 acts to release the latch member 78 from engagement with the arm 76 which has been swung upwardly by the depression of the 100 key. Such release of the arm 76 permits of the movement thereof, and consequently of the rod 67, by the spring 80, whereby to cause the latch member 66 to become disengaged from its notch 77 in the rod 17. The result is that as soon as the selector bar becomes positioned over file unit 123, its connection with the operating rod is rendered ineffective so that stoppage of the bar immediately takes place. The engagement of the contact device 46 with the tab 35 of the file unit tends to open such unit (Fig. 5) thus permitting of the easy insertion of papers into the file or the removal of papers therefrom.

Should it be desired to select a unit of the first division, as for example, unit 13, no depression of any of the keys 19^a becomes necessary since the first selector bar 16 is at all times connected with the operating rod through the medium of the latch mechanism 18^a, (Fig. 3) such connection being rendered ineffective when the keys 19^a are operated for the selection of any of the other bars.

In case it is desired to select the first unit of any division as, for example, unit 100, this may be accomplished without depress-

ing the keys 19^a or 19^b since the circuits controlled by such units and tens keys is normally closed through the medium of the contact members 58 and 59 connecting respectively pairs of contact members 56 and 57, the contact members 56 being connected respectively with the contact device of the selector bar 16 for the 100 unit, and with the battery; and the contact members 57 being respectively connected with the set 15 containing the 100 unit, and with the battery.

After the particular unit which it is desired to select has been indicated by the proper selector bar, the operator ceases to actuate the rod 17 until the desired filing operation has been completed. Thereupon, the rod 17 is moved to the forward limit of its stroke which causes the collar 22 to engage with the arm 94 of the key releasing mechanism. Upon such release of the keys, the circuits established thereby are broken. Thereupon, the rod is moved to its rearmost position and in this movement, the abutments 31 thereon engage with the plates 65 depending from the selector bars and restore any bars which have been moved, to their initial positions for another operation.

It will be seen that the invention provides in general a system whereby the selective designation of certain of the units of a group or series may be effected quickly and easily. Thus it provides a distributing system which is capable of greatly facilitating the operation of filing letters, cards, or the like, or in distributing any other matter according to a predetermined order. The preliminary sorting of the matter to be filed is eliminated, and at the same time the speed and accuracy with which the distribution may be accomplished is relatively great.

It is desired particularly to point out that the invention is not intended to be limited to the particular means herein disclosed for designating the particular unit which it is desired to select since other means may readily be devised without departing from the spirit and scope of the invention.

I claim as my invention:

1. An apparatus of the character described comprising, the combination with a filing drawer having a plurality of filing units therein arranged in a definite order, of a plurality of bars movable relative to said units and adapted to engage therewith, key-controlled electro-magnetic circuits adapted to be closed in the movements of said bars by contact with said filing units, and mechanism operable upon the closing of said circuits to cause said bars to designate certain of the filing units as determined by the manipulation of the keys.

2. An apparatus of the character described, comprising, the combination with a plurality of units arranged in a definite or-

der and adapted to be supported in upright position, of a plurality of devices movable relative to said units and adapted to engage therewith, key-controlled electro-magnetic circuits adapted to be closed by the contact of said devices with said units, and mechanism operable upon the closing of said circuits to cause said devices to designate certain of the units as determined by the manipulation of the keys.

3. An apparatus of the character described comprising, the combination with a filing drawer having a plurality of file units therein arranged in a definite order, of a casing into which said drawer may be inserted, means in said casing forming with each file unit part of an electro-magnetic circuit and movable simultaneously into engagement with all of the file units so as to form key-controlled electrical connections therewith, means movable into engagement with the successive file units and adapted to complete said electro-magnetic circuits, and mechanism operable upon the engagement of said means with a predetermined file unit whereby to designate such predetermined unit.

4. An apparatus of the character described comprising, the combination with a plurality of units arranged in a definite order, of means arranged to form with each of said units a key-controlled electro-magnetic circuit normally open, and means for closing the circuit containing a particular unit selected by the operation of a key.

5. An apparatus of the character described comprising, in combination, a plurality of separating units, means for supporting said units, means including devices movable into engagement with said units successively adapted to provide an electro-magnetic circuit with each of said units, keys for controlling each of said circuits, and mechanism operable upon the engagement of a device with the unit in the circuit selected by the depression of one or more of said keys whereby to actuate the electro-magnet in said circuit and cause such device to designate said unit.

6. An apparatus of the character described comprising, the combination with a group of file units arranged in a definite order, of means adapted to designate a predetermined one of said units including an indicating device, means for actuating said device, and means automatically operable in the movement of said device to cause it to designate the predetermined unit.

7. An apparatus of the character described comprising, in combination with a plurality of separator units of means for supporting said units in a predetermined order, means for establishing with each of said units an electric key-controlled circuit, including an operating member, a plurality

of switch devices for said circuit, means carrying said switch devices, and latch mechanism adapted to connect said operating member with said switch-carrying means whereby the switch devices may be moved into engagement with the units successively, and electro-magnetic means operable upon the engagement by one of said devices with a predetermined unit to operate said latch mechanism and thereby release the switch-carrying means from further movement by the operating member.

8. In an apparatus of the character described, the combination with a plurality of 15 separator units arranged in a definite order and divided into divisions with the divisions subdivided into sets, of means for forming with each set a portion of an electric circuit, means adapted to form with each of said 20 units another portion of an electric circuit, including means operable to close each of said circuits by contact with said units, a series of keys in each of said portions of the circuit, and mechanism operable upon the 25 depression of one or more of said keys to effect a designation of a corresponding unit or units.

9. In an apparatus of the character described, the combination of a plurality of 20 separator units, means adapted to form with each of said units an electric circuit, controlling means for said circuits whereby a particular circuit may be selected, and means operable upon such selection of a circuit to designate the particular unit included in that circuit.

10. In an apparatus of the character described, the combination with a plurality of separator units, of means for designating 40 a given one of said units including an electro-magnetic circuit, and key-operated means for controlling the circuit.

11. In an apparatus of the character described, the combination with a plurality of 45 separator units, of means for designating a given one of said units including an electric circuit, an electro-magnet in said circuit, an indicator device operatively associated with said magnet, and manually operable 50 means for controlling said circuit.

12. In an apparatus of the character described, the combination with a plurality of separator units, of means for designating a given one of said units including an electric 55 circuit, an electro-magnet in said circuit, an operating member, an indicator device adapted to be operatively connected with said operating member and operatively associated with said magnet whereby the latter is adapted to release the connection between said device and member, and means for controlling the circuit.

13. In an apparatus of the character described, the combination of a plurality of 65 separator units, means for dividing the units

into divisions, and means for designating certain of said units including an electric circuit having an electro-magnet therein for each division, an indicator device for each division, an operating member, means controlled by said magnet for connecting any one of said devices to said member, key-operated means for controlling said connecting means whereby to select the device for the division to be operated upon and containing the unit to be selected, and key-operated means for controlling said electric circuit to select the desired unit of such division.

14. In an apparatus of the character described, the combination of a plurality of separator units, means for dividing the units into divisions, and means for designating certain of said units including an electric circuit having a plurality of electromagnets 80 therein, a plurality of indicator devices, an operating member, means controlled by said magnets for connecting said devices to said member, key-operated means for controlling said connecting means whereby to select the device for the division to be operated upon and containing the unit to be selected, and key-operated means for controlling said electric circuit to select the desired unit of such 85 division, one of said indicator devices being normally connected by said connecting means to the operating member and the others normally disconnected.

15. In an apparatus of the character described, the combination of a plurality of separator units, means for dividing the units into divisions, and means for designating a desired unit including an indicator device for each division, a plurality of electric circuits having controlling keys whereby any desired unit in the several divisions may be selected for designation, key-controlled mechanism for selecting the indicator device of the division in which the desired one of said units is found, and mechanism under the control of said electric circuits for operatively associating the indicator device selected by the operation of one of said last-mentioned keys with the desired unit in such division whereby to effect a designation thereof.

16. In an apparatus of the character described, the combination of a plurality of separator units, means for dividing the units into divisions, and means for designating a desired unit including an indicator device for each division, a plurality of electric circuits having controlling keys whereby any desired unit in the several divisions may be selected for designation, key-controlled mechanism for selecting the indicator device of the division in which the desired one of said units is found, means for moving the indicator device selected by the operation of one of said last-mentioned keys into engage- 120 125 130

- ment with the desired unit in such division whereby to close the circuit in which said unit is found, and means operable upon the closing of such circuit to designate the desired unit.
17. In an apparatus of the character described, the combination of a plurality of separator units, means for dividing the units into divisions, and means for designating a desired unit including an indicator device for each division, means adapted to form electric circuits with the corresponding units of the several divisions, keys for controlling said circuits, key-controlled mechanism for selecting the indicator device of the division containing the desired unit, and mechanism under the control of said electric circuits for operatively associating the selected indicator device with the desired unit in its division whereby to effect the designation thereof.
18. In an apparatus of the character described, the combination of a plurality of file units, a drawer for containing said units arranged in sets with the units of each set electrically connected together, and means adapted to form with any desired unit of a given set a key-controlled electric circuit having an electromagnet therein, and mechanism operatively associated with said magnet whereby to effect a designation of one of said units as determined by the depression of a key.
19. The combination set forth in claim 18 wherein the sets of units are each formed from a single piece of metal divided and folded to form a plurality of units.
20. In an apparatus of the character described, the combination of a plurality of file units formed from a single piece of material divided to form flaps which are each swingable from flat or extended relation through an arc of one hundred and eighty degrees with reference to the adjacent flap whereby to provide separate divisions for the reception of material to be filed.
21. In an apparatus of the character described, the combination of an electric circuit including a unit to be selected and a movable contact, means for moving the contact and an electro-magnet in such circuit operable upon the engagement of said contact with the unit to effect the stoppage of the contact.
22. In an apparatus of the character described, the combination of an electric circuit including a unit to be selected, a contact member, a carrier bar for said member, and electro-magnetically controlled means for moving said bar until said contact member engages such unit.
23. In a device of the class described, the combination of a unit to be selected, of electro-magnetically controlled means for selecting such unit, including an electro-magnet, a contact in circuit with said magnet, and means for moving said contact into engagement with the unit.
24. In a device of the class described, the combination of a unit to be selected, of electro-magnetically controlled means for selecting such unit including a controlling device having a normally broken electrical connection with the unit, a contact member movable into and out of engagement with said unit, a second controlling device also having a normally open electrical connection with said contact member, and means for moving said contact member.
25. In an apparatus of the character described the combination with a plurality of units arranged in a definite order, of electro-magnetically controlled means for selecting a predetermined one of said units, said means including key-controlled means providing a continuous electrical connection between any one of said units and one pole of a source of electric energy, and key-controlled means providing an electrical connection between the other pole of said source of energy and said unit.
26. In an apparatus of the character described the combination with a plurality of units arranged in a definite order, of electro-magnetically controlled means for selecting a predetermined one of said units, said means including a source of electric energy, key-controlled means providing a continuous electric connection between one pole of said source of energy and a given one of the units, a plurality of contact members movable into engagement with said units successively, and key-controlled means providing a continuous electrical connection between a given one of said contact devices and the other pole of said source of energy.
27. In an apparatus of the character described the combination with a plurality of units arranged in a definite order, of means for automatically selecting a predetermined one of said units, said means including an indicator device movable into contact with said units successively, and mechanism operating to cause said device in such movement to designate said predetermined unit.
28. In an apparatus of the character described the combination with a plurality of units arranged in a definite order, of means for selecting a predetermined one of said units, said means including an indicator device movable into contact with said units successively, and means for moving said device comprising an operating member and means under the control of the operator for connecting said indicating device with said operating member.
29. In an apparatus of the character described the combination with a plurality of units arranged in a definite order, of means for selecting a predetermined one of said units, said means including an indicating

- device, an operating member, an electro- units, said means including a part adapted magnet, and mechanical means operatively associated with said magnet for effecting a connection between said device and said operating member.
30. In an apparatus of the character described, the combination with a plurality of units arranged in a definite order, of means for selecting a predetermined one of said units, said means including a member movable with respect to said units, an operating member, an electro-magnet, and a latch device operatively associated with said magnet and adapted to effect a connection between said operating member and said movable member.
31. In an apparatus of the character described, the combination with a plurality of units arranged in a definite order, of means for selecting a predetermined one of said units, said means including an indicating device and an operating member therefor, and key-actuated means for effecting a connection between said operating member and said indicating device.
32. In an apparatus of the character described the combination of a plurality of units arranged in a definite order, of means for selecting a predetermined one of said units, said means including an indicating device, an operating member, a latch device adapted to connect said operating member and said indicating device, and manually operable means for actuating said latch device.
33. In an apparatus of the character described, the combination with a plurality of units, of means for selecting a predetermined one of said units, said means including an indicating device, an operating member, a latch device adapted to connect said operating member and said indicating device, manually operable means for actuating said latch device in one direction, spring-actuated means operable to hold said latch device in its operative position, and means including an electro-magnet adapted to render said holding means ineffective.
34. In an apparatus of the character described the combination with a plurality of units, of means for selecting a predetermined one of said units, said means including an operating member, a part to be connected with said member for movement thereby, key-actuated means operable to effect such connections, means for retaining said mechanism in its connected relation, and means operable automatically in the movement of said operating member to release said retaining means whereby to disconnect said part from the operating member.
35. In an apparatus of the character described the combination with a plurality of units arranged in a definite order, of means for selecting a predetermined one of said
- units, said means including a part adapted for movement with respect to said units, operating means, mechanism adapted to effect a connection between said part and said operating means, and means operable automatically in the movement of said part to effect the release thereof from said operating means by said mechanism.
36. In an apparatus of the character described the combination with a plurality of units, means dividing the units into divisions and the units of each division into sets, and means operable to effect the designation of a predetermined one of said units, said means including a source of electric energy, means providing a normally closed electrical connection between the units of one set of each division and the source of electric energy, means providing normally open connections between the remaining sets of each division and such source of electric energy, and key-actuated switch devices each operable to break the first or closed connection and then to close one of the second or open connections.
37. In an apparatus of the character described the combination of a plurality of units, means dividing the units into divisions and the units of each division into sets, and means operable to effect the designation of a predetermined one of said units, said means including a source of electric energy, a device for each division movable into contact with a certain one of the units of each set in the division, means providing a closed connection between said unit and the source of electric energy when said device is in contact with said unit, and means providing a normally closed connection between the other pole of said source of electric energy and the set including the desired unit.
38. In an apparatus of the character described the combination with a plurality of file units arranged in a definite order, of means for selecting a predetermined one of said units, said means including devices movable into electrical contact with any one of said units, a source of electric energy, key-controlled means for effecting an electrical connection between said units and one pole of said source of electric energy, key-controlled means for effecting a connection between any one of said devices and the other pole of said source of electric energy, and means operable upon the completion of a circuit with any one of said units to effect the stoppage of the corresponding device.
39. In an apparatus of the character described the combination with a plurality of file units, of means for selecting a predetermined one of said units, said means including devices movable into electrical contact with said units, a source of electric energy, manually-controlled means for effecting an electrical connection between said

units and one pole of said source of electric energy, manually-controlled means for effecting a connection between any one of said contact devices and the other pole of 5 said source of electric energy, and means operable upon the completion of a circuit to indicate the particular unit therein.

40. In an apparatus of the character described in combination with a plurality of 10 units arranged in a definite order, of means for designating a predetermined one of such units including means adapted to provide an electrical connection between any one of said units and a source of electric energy, a plurality 15 of movable contact devices adapted to engage successively with said units, means for effecting an electrical connection between the opposite pole of said source of electric energy and the one of said devices which is 20 adapted to contact such predetermined unit, and means operable upon the completion of the circuit by such contact to effect the designation of such unit.

41. A system of distribution comprising, 25 in combination with a plurality of filing units, a receptacle containing said filing units arranged in a definite order, of a plurality of selector devices, means for moving said devices relative to said filing units, electro-magnetic means adapted to be electrically connected with said devices, and a keyboard 30 operatively associated with and adapted to control said means whereby upon the movement of a selector device longitudinally with reference to said drawer the designation of 35 a desired filing unit may be effected.

42. The method of distribution which consists in moving a selector device relative to a filing drawer or other receptacle and across 40 the file units contained therein, and stopping the selector device, by means of key-controlled electro-magnetic means, in position over a given file unit.

43. The method of distribution which 45 consists in placing each of a series of file units in an electric circuit, and controlling said circuits by means of keys whereby to operate electrically indicating means for designating the particular unit desired.

44. The method of distribution which 50 consists in arranging a plurality of units in a definite order, grouping the units into sets, placing the set of units containing the unit to be selected into a normally open electro-magnetic circuit by depressing a key, placing in

said circuit one of a plurality of switch members corresponding in number to the number of units in each set by the depression of another key, and finally completing the selection of the desired unit through the medium 60 of mechanism set in operation by the closing of said circuit by moving the several switch members into engagement with their corresponding units in the several sets whereby the circuit controlled by the depressed keys 65 becomes closed when the switch member in said circuit comes in contact with its unit of the set in said circuit.

45. The method of filing which consists in arranging a plurality of filing units in a 70 definite order, placing the unit which is to be selected in a normally open electro-magnetic circuit by depressing one or more keys, and moving a switch member into engagement with successive units including the unit 75 in said circuit to close the latter and set in operation means for designating the desired unit.

46. The combination of a group of filing 80 units arranged in a definite order, and key-controlled electromagnetic means for automatically selecting a predetermined one of said units according to its position in said order.

47. An apparatus of the character described comprising, in combination with a source of electric energy, a unit to be indicated, an electrically controlled indicator therefor, a plurality of sets of key-switches, and electrical connections between said source 90 and said key-switches and between said key-switches and said indicator, said connections being adapted to close the electrical circuit to said indicator upon closing of a predetermined combination of said key-switches. 95

48. The combination with a plurality of units to be designated selectively, of a source of electric energy, means for electrically connecting each of said units to opposite sides of said source of energy and said means constituting normally open circuits, one for each of said units, and two sets of switches controlling the respective connecting means, the closing of one switch in each set being adapted to complete a circuit, and means operative upon the closing of said circuit to indicate the unit contained therein. 100 105

In testimony whereof, I have hereunto set my hand.

IRENE WHETSTONE.
